UNITED STATES PATENT OFFICE.

WILLIAM A. BROWN, OF NEW YORK, N. Y.

DESIGN FOR A SPOON.

SPECIFICATION forming part of Design No. 29,662, dated November 15, 1898.

Application filed October 18, 1898. Serial No. 693,930. Term of patent 7 years.

To all whom it may concern:

Be it known that I, WILLIAM A. BROWN, a citizen of the United States, and a resident of New York city, county of New York, and State 5 of New York, have invented and produced a certain new and useful Design for Spoons; and I do hereby declare the following to be a full, clear, and exact description of the invention, such as will enable others skilled in the 10 art to which it appertains to make and use the same.

My invention consists in the design for spoons illustrated in the accompanying drawings and described in the following specification.

In the drawings, Figure 1 is an elevation of the obverse of the spoon, and Fig. 2 is a similar view of the reverse of the same.

The general design of this spoon is intended 20 to be symbolical of the birth of the American flag, and, as shown in Fig. 1, the enlarged upper end of the handle contains in bas-relief a portrait *a*, intended to represent Betsy Ross, the woman who made the first flag of 25 this country. The figure is seated and appears facing the observer in about a three-quarter position and the woman is shown clad in the Continental costume which was fashionable during the period of the Revolutionary war, including a cap on the head and 30 a kerchief thrown around the shoulders. Upon the lap of the woman lies an unfinished American flag *b*, and she is represented as in 35 the act of sewing on it. The design of the flag is that first made by Betsy Ross, having the white stars arranged in a circle on the blue field. The portion of the flag which is formed in stripes falls gracefully over the woman's knees and extends below her feet 40 into the tapering part of the handle between the shank and the upper end, the outline of this intermediate part being formed by the folds of the flag. Surrounding the figure thus described there is a conventional scroll-work border *c*, forming an ornamental frame 45 or setting for the figure and defining the contour or outline of the enlarged end of the spoon at the sides and top.

The shank of the handle (that part between 50 the end of the flag and the bowl) is outlined

and ornamented by a scrollwork border *d*, conforming in general effect to the border on the upper end, and the scrollwork on the opposite edges unites at the junction of the handle with the bowl, where it is formed into 55 a conventional flower-like ornamentation *e*, extending into the bowl of the spoon.

In addition to the above ornamentation the shank of the handle has upon its central portion a ribbon *f*, which is represented as coming from the reverse side of the upper part of the handle and as wound around the part just above the ornament *e*, whence it extends into the bowl in large flowing waves *f'*.

The outline of the reverse of the handle is 65 practically like that of the obverse, as will appear on inspection of Fig. 2, but in the upper end, in the place corresponding to that of the portrait of Betsy Ross, is a bas-relief representation *g* of the house where the first 70 American flag was made, and which is now standing at No. 239 Arch street, Philadelphia, Pennsylvania. Beneath this representation of Betsy Ross' house and in the tapering part of the handle appears the upper end *f''* of the 75 same ribbon which is represented on the obverse side lower down, this end of the ribbon being shown as arranged in scroll-like order centrally of the width of the handle. On either side of the ribbon and forming the 80 contour of this side of the handle is a leaf-like scrollwork border *h*.

The reverse of the bowl is perfectly plain except for a small conventional flower-like ornamentation *i*. 85

Having thus described my design, what I claim is—

1. In the design for a spoon, the obverse, substantially as herein shown and described.
2. In the design for a spoon, the reverse, 90 substantially as herein shown and described.
3. The design for a spoon, substantially as herein shown and described.

In testimony whereof I affix my signature in presence of two witnesses.

WILLIAM A. BROWN.

Witnesses:
